UNITED STATES PATENT OFFICE.

GUSTAVE C. KUTZ, OF CLEVELAND, OHIO, ASSIGNOR OF ONE-HALF TO JOHN HARRIS, OF CLEVELAND, OHIO.

MARKING-MACHINE.

No. 925,928.

Specification of Letters Patent.

Patented June 22, 1909.

Application filed February 29, 1908. Serial No. 418,452

To all whom it may concern:

Be it known that I, GUSTAVE C. KUTZ, a citizen of the United States, residing at Cleveland, in the county of Cuyahoga and State of Ohio, have invented a certain new and useful Improvement in Marking-Machines, of which the following is a full, clear, and exact description, reference being had to the accompanying drawings.

10 This invention relates to indorsing machines generally, and more particularly to machines which are employed for the purpose of indorsing checks.

The invention has for its object the provision of a machine of this kind which is adapted for use in connection with an adding machine, whereby the operation of the adding machine will cause the operation of the indorsing machine.

20 A further object of this invention is to provide a machine of this character which is comparatively simple of construction and efficient in operation.

Generally speaking, the invention may be 25 defined as consisting of the combinations of elements embodied in the claims hereto annexed and illustrated in one form in the accompanying drawings, wherein—

Figure 1 represents a perspective view of 30 my machine, showing the manner in which the same is used in connection with an adding machine, said adding machine being also represented in perspective; Fig. 2 represents a top plan view of my machine; Fig. 3 represents a side elevation; Fig. 4 a central longitudinal sectional view of the same, and Figs. 5 and 6 represent details of construction.

Describing the parts by reference characters, 1 represents the indorsing machine generally, the same comprising a casing which is mounted upon a standard 2 which is telescopically mounted in a sleeved projection of a base 2^a. The machine is detachably connected to the upper end of standard 2 by 45 means of a lateral arm 3 threaded onto the upper end of said standard and a vertical supporting arm 4 carried by arm 3.

The machine proper comprises a casing 5 having a glass top 6.

50 7, 7^a denote a pair of brackets extending downwardly from the base of the casing. These brackets support the main operating shaft 8 for the machine, said shaft extending outwardly beyond one side of the machine 55 and being provided at its outer extremity

with an operating arm or lever 9 which is secured to the outer end of said shaft by means of a sleeve 10 and set screw 11. The outwardly extending portion of shaft 8 is supported by a sleeve 8^a. Arm 9 is provided 60 with an operating member 12, said member having a sleeve 13 adapted to be slipped onto arm 9 and having a set screw 14 by means of which it may be clamped to said arm. The end remote from sleeve member 65 12 is forked and is provided with a roller 15 journaled between the forks.

16 denotes a collar mounted on arm 9 and serving as a stop or adjustment for member 12. The roller 15 is adapted to be engaged 70 by the crank 17 of an adding machine 18 whereby, when the crank 17 is depressed to record the number set up by the depression of the keys 19, shaft 8 will be rocked and the indorsing mechanism will be operated in a 75 manner to be described hereinafter.

When it is desired to operate the adding machine independently of the indorsing machine, set screw 14 will be loosened and member 12 will be dropped out of the way of 80 crank 17. When it is desired to operate the indorsing machine by the adding machine, it will be necessary only to swing member 12 to an upright position and set up on screw 14, the collar 16 serving to locate the member 85 properly with reference to the crank 17.

In operation, the adding machine will be mounted on some suitable support, and the capacity for vertical adjustment of my indorsing machine enables the same to be applied 90 to the adding machine without interfering with the adjustment of the latter.

The bottom of casing 5 is provided with a pair of upwardly projecting guides 20 provided each with a threaded aperture for the 95 reception of a nut 21. These nuts provide a guideway for the operating stem 22 which carries the indorsing stamp 23 at its front end. As will appear by reference to Figs. 2 and 4, the indorsing stamp is rotatably 100 mounted between forwardly projecting yoke arms 24 connected by a transverse arm 24^a carried by a short stem 25 which is detachably fitted within a socket at the front end of stem 22. A heavy washer 26 of rubber or 105 other resilient material is applied to stem 22 at the rear of transverse arm 24^a and is for the purpose of absorbing the shock due to the return of the stem to the position shown in Fig. 4 after the printing operation. A simi- 110

lar washer 27 is applied to stem 22 at the rear of bracket 20 and absorbs the shock when the stem reaches its forward limit of movement.

5 28 denotes a spring surrounding stem 22 and having its rear end engaging a stop collar 29 and its front end in engagement with the rear end of nut 21.

10 30 denotes a platen which is supported by the bottom of the casing and projects upwardly from the front end thereof. The rear face of this platen is inclined downwardly and rearwardly from the top thereof.

15 31 denotes a chute member which cooperates with platen 30 to form a chute and a temporary receptacle for the checks or other articles which are to be indorsed. Member 31 is preferably a casting and is provided with a pair of end flanges 32, the front faces 20 whereof are inclined to conform to the rear face of platen 30. Flanges 32 are connected by a transverse plate 33 which extends across the front of the casing proper and is provided with a rearwardly projecting ledge 34 25 which fits between the corner posts 35 at the front of the casing. Plate 33 is slightly inclined forwardly from the top to the bottom thereof and is provided with a central longitudinal recess 36 therein and has its lower 30 end projecting downwardly below the bottom of the casing, forming with the lower end of platen 30 a slot 37 through which the articles may pass after indorsement.

35 38 denotes an inking roller which is mounted on a shaft 39 journaled in opposite arms of a yoke 40 which is mounted on a curved arm 41 connected to a shaft 42 which is located at the rear of stamp 23 and is journaled between standards 43 projecting upwardly from the bottom of the casing. A spring 44, having one end connected to a stud 45 projecting downwardly from the bottom of the casing and its other end connected to a rod 46 projecting from shaft 42, normally retains the inking roller in front of aperture 36 and between the same and the stamp 23.

50 Stamp 23, to which reference has been made hereinbefore, is pivotally mounted between the yoke arms 41, as hereinbefore described. This stamp comprises a block which is preferably angular in section, the block shown having four sides to each of which there is applied a printing pad of rubber or similar material having thereon printed characters corresponding to the indorsement which it is desired to apply to the check or similar article deposited in the chute formed between platen 30 and member 32. 55 The block comprises two symmetrical members connected in the manner shown in Fig. 4; that is to say, by means of male and female screws 23^a, 23^b applied to the opposite block members and having their heads located within recesses in the surfaces of said mem-

bers. This permits the block to be applied conveniently to the shaft 47, by means of which the stem is mounted in the arms 41. The block will be supported with the front face thereof and the pad 48 thereon substantially parallel with the inclined rear surface of platen 30 and the parts will be so arranged that the upper end of the pad 48 will bear against the inking roller 38 slightly above the center of shaft 39. 49 denotes a flat 70 spring which is connected to one of the arms 41 with its front end fitted within one of the recesses 50 of hand wheel 51 connected with shaft 47. This construction is illustrated in Figs. 2, 3 and 6. From the last-mentioned 75 figure, it will be apparent that the recesses 50 correspond in number to the faces of the stamp and that the arrangement is such that, when the front end of spring 49 is in one of said recesses, the front face of stamp 23 will 80 be substantially parallel with the rear face of platen 30.

85 For the purpose of operating the stamp pad toward and from the platen 30, I provide the following construction:

90 52 denotes an arm which is rigidly connected to shaft 8. To the upper end of this arm there is connected a link 53, the rear end of which is connected to an operating pin 54 the upper end whereof is rigidly connected 95 with stem 22, as by being threaded thereinto. When arm 9 is depressed, shaft 8 will be rocked, carrying stem 22 forwardly. The manner of mounting roller 38 and the angle at which the front face of the inking pad engages the same causes the roller to be depressed by the stamp, inking the front face of the stamp. The front face of stamp 48 will engage the check or other article resting against platen 30 and will impress thereon 100 the appropriate indorsement, the blow of the stamp being cushioned by washer 27. On releasing the arm 9, spring 28 returns stem 22 to the position shown in the drawings, the yielding washer 26 cushioning the blow of 105 the stamp against nut 21.

110 In conjunction with the above described apparatus, I employ means for retaining the checks in place during the printing operation and for automatically releasing the same and 115 permitting them to be discharged into a receptacle 55 after they have been indorsed. Receptacle 55 is located immediately below the chute provided by platen 30 and member 32 and has its front end open and provided 120 with a gate 56 pivoted between the opposite sides thereof and provided with a spring 57 which normally holds the vertical branches of said gate against the bottom of the receptacle. To accomplish the automatic release 125 of the checks or other indorsed articles, I employ retaining devices consisting of a pair of rods with mechanism for actuating the same in such manner that the free ends of these rods normally block the passageway 130

between the chute and the receptacle with means for automatically withdrawing said rods to permit the checks or other printed articles to pass from the chute into the receptacle after a printing operation. These rods are represented at 58 and are provided at their front end with collars 59 which, when the rods are in the position shown in Fig. 4, block the discharge outlet 37 from the chute. 5 These rods are mounted in guides 60 depending from the base of the casing and are each provided with a stop collar 61 adjustably secured thereto. For the purpose of operating these rods, I provide a rock shaft 62 mounted 10 in bearings formed in brackets 63 and connect said rock shaft with main operating shaft 8 by means of an arm 64 rigid with shaft 62, link 65 and arm 66 rigid with main operating shaft 8.

10 These rods are mounted in guides 60 depending from the base of the casing and are each provided with a stop collar 61 adjustably secured thereto. For the purpose of operating these rods, I provide a rock shaft 62 mounted 15 in bearings formed in brackets 63 and connect said rock shaft with main operating shaft 8 by means of an arm 64 rigid with shaft 62, link 65 and arm 66 rigid with main operating shaft 8.

20 On rock shaft 62 are rigidly mounted a pair of disks 67, each having a pair of spaced studs 68 adapted to engage an arm 69 which is loosely mounted on shaft 62 and has its lower end connected to the rear end of a rod 25 58 by a pin-and-slot connection 70. As will appear by reference to Figs. 3 and 4, which represent the positions assumed by the parts immediately after the return of the stamp 23 by spring 28, the rearward movement of stem 22 by said spring causes shaft 8 to be rocked in a counter clock wise direction, thereby causing the lower studs 68^a on disks 67 to engage the arms 69 and force the rods forwardly to the position shown in said figures. When shaft 8 is rotated in a clock wise direction, as when the arm 9 is depressed by the crank 17 of the adding machine, the front printing face of pad 23 will be brought into engagement with the check 30 or similar article on platen 30 nearly simultaneously with the engagement of the upper studs 68 on disks 67 with arms 69, which moves the rods 58 rearwardly. When arm 9 is released, ample opportunity is afforded for 35 the check or other indorsed article to be dropped from the chute into the receptacle; 40 55 by reason of the lost-motion connection between the rods 58 and the stem 22 afforded by the space provided between studs 68 and 50 68^a, which compels rock shaft 62 to rotate the angular distance between said studs less the width of arm 69 before the lower studs 68^a engage said arms and move the rods forwardly again.

55 In operation, the operator sets up on the keys of the adding machine the amount shown on the check and depresses the crank 17 to record such amount. As soon as he depresses the keys on the adding machine, he 60 deposits the check in the chute with its face applied to the inclined face of the platen. He then depresses lever 17 to record the amount of the check. This lever engages roller 15 on arm 9 and rocks shaft 8. The 65 rocking of shaft 8 causes the printing stamp to advance depressing roller 38 out of the way, which inks the pad on the front of the stamp. The pad then impresses upon the back of the check the appropriate inscription. 70 On releasing the crank 17, spring 28 restores the parts to the position shown in the drawings. Just before the end of its rotation by the downward movement of arm 9, shaft 8, through the connections hereinbefore described, causes the arms 58 to be withdrawn 75 from beneath the slot 37 and these arms are retained in this position until just before the end of the reverse movement of shaft 8 by stem 22 and spring 28, whereupon the rods are again moved forward in position to close 80 the bottom of the chute for the next check which may be inserted thereinto. By the construction described, I have provided means whereby the rotation of shaft 8 automatically causes the inking of the pad by the 85 roller 38 and moves said roller out of the way of the forward movement of said pad and whereby the check or other article placed in the chute is retained therein until the appropriate inscription has been printed thereon. 90 The stamp is then automatically returned to its initial position and the check or other article is discharged from the chute into the appropriate receptacle.

95 To adjust the machine as occasion may require, I provide arm 52 and link 65 with a series of apertures by means of which the points of connection of the same with link 53 and arm 64 respectively may be varied. The stem 22 and the spring theron may be covered by a curved plate 71 removably fitted to the tops of standards 20. To prevent the roller 38 from being elevated so far by its spring 44 as to interfere with or prevent the 100 operation of the printing stamp, I provide a stop to limit the upward movement of said roller, said stop comprising a projection 42^a 105 extending rearwardly from shaft 42 and a rubber bumper 42^b for said projection.

110 By reference to Fig. 4, it will be seen that some clearance is provided between the front ends of rods 58 and the portion of the base plate which is immediately below the platen 30. Should it happen that the rods 58 are returned to the position shown in Fig. 4, before a check has entirely passed from the chute into receptacle 55, the only effect 115 would be to tilt the check, but, owing to the clearance, the check can pass into receptacle 55.

120 Having described my invention, I claim:

1. In a machine of the character set forth, the combination of an inclined platen, a horizontally reciprocating printing device having a correspondingly inclined printing surface, 125 means for moving said device toward and from said platen, a curved arm pivoted at the rear of said printing device and having its front end interposed between the printing device and the platen, a spring connected 130

with said arm and tending to elevate the front end thereof, an inking roller carried by the front end of said arm, and a stop for limiting the elevation of said arm by said 5 spring.

2. In a machine of the character set forth, the combination of a chute comprising a front platen and a rear plate having an aperture therethrough, a printing device, means 10 for moving the said printing device, and an inking roller yieldingly supported between said printing device and the aperture in said plate and adapted to be moved out of the path of the printing device by the forward movement 15 of said device.

3. In a machine of the character set forth, the combination of a platen, a pair of standards, a stem supported by said standards, a printing device supported by said stem, a 20 washer of resilient material on said stem in front of said standards, a spring on said stem tending to move the same rearwardly, a shaft, and a connection between said shaft and said stem adapted to move said stem 25 forwardly against the resistance of said spring.

4. In a machine of the character set forth, the combination of a chute, a pair of sliding chute-closing members, an operating shaft, a 30 printing device, a platen, connections between said shaft and the printing device adapted to move the latter toward the platen, a second shaft, connections between said shafts whereby the rotation of the former shaft will rotate the latter shaft, arms sleeved on the latter shaft and connected with the chute-closing members, and lost-motion connections between the latter shaft and said arms.

40 5. In a machine of the character set forth, the combination of a chute, a sliding chute-closing member, an operating shaft, a printing device, a platen, connections between said shaft and the printing device adapted to 45 move the latter toward the platen, a second shaft, connections between said shafts whereby the rotation of the former shaft will rotate the latter shaft, an arm sleeved on the latter shaft and connected with a chute-closing 50 member, and a lost-motion connection between the latter shaft and said arm.

6. In a machine of the character set forth, the combination of a platen and a chute, a printing device, a shaft, connections between 55 said shaft and said printing device for moving the same toward the platen, a chute-closing member, a second shaft, connections for rotating the latter shaft by the movement of the former shaft, an arm loosely mounted on 60 the latter shaft and engaging the chute closing member, and a disk rigid with said latter shaft and having a pair of spaced projections adapted to engage said arm to operate the chute-closing member in opposite directions.

65 7. In a machine of the character set forth,

the combination of a casing having a chute at the forward end thereof, said chute having its front wall formed as an inclined platen, a stem having at the front end thereof a printing device provided with a correspondingly 70 inclined printing surface, guides below said casing, a chute-closing member reciprocably mounted in said guides, a shaft, connections between the first-mentioned shaft and the latter shaft, an arm rigid with the second 75 shaft and connected to said member, and spaced members for engaging opposite sides of said arm, said spaced members being carried by the latter shaft and adapted to engage opposite sides of said arm. 80

8. In a machine of the character set forth, the combination of an inclined platen, a printing device having thereon a plurality of printing surfaces, means for retaining said printing device with any one of its surfaces 85 parallel with said platen, an inking roller interposed between said device and said platen, and means for flexibly supporting said roller in position to be engaged by the inclined front face of the printing device and to be 90 moved by such face out of the path of movement of the printing device.

9. In a device of the character described, the combination of a chute comprising a front platen and a rear plate having an opening therethrough, a printing device, means 95 for moving said printing device toward said platen, an inking roller interposed between said printing device and the rear platen, said roller being moved out of the path of the 100 printing device upon the forward movement of the printing device, and means normally closing the bottom of the chute, said means being movable upon the movement of the printing device to open and close the bottom 105 of the chute.

10. In a device of the character described, the combination of a chute comprising a front inclined platen and a rear plate having an opening therethrough, a printing device, 110 the surface of which extends in a direction parallel to the inclined front platen, means for moving said printing device toward said plate, an inking roller interposed between said printing device and the aperture in the 115 rear plate, said roller being moved out of the path of the printing device upon the forward movement thereof, and means normally closing the bottom of the chute, said means being movable upon the movement of the printing 120 device to open and close the bottom of the chute.

11. In a device of the character described, the combination of a chute having an inclined platen as a part thereof, a horizontally 125 reciprocating printing device, the printing face of said device extending in a direction parallel to the inclined platen, an inking roller interposed between the printing device and the platen, said roller being engaged by 130

the printing surface of the printing device and moved out of the path thereof upon the forward movement of the said printing device, and means normally closing the bottom 5 of the chute, said means being movable upon the movement of the printing device to open and close the bottom of the chute.

12. In a device of the character set forth, the combination of a chute, comprising a 10 front platen and a stationary rear plate having an opening therethrough, a printing device adapted to reciprocate through said opening, means for moving said printing device toward said platen, and means to normally 15 close the bottom of the chute, said means being movable upon the movement of the printing device to open and close the bottom of the chute.

13. In a device of the character described, 20 the combination of a chute having a platen therein, a reciprocating printing device, mechanism for moving the printing device in a direction to print, and independent mechanism for moving the printing device to its 25 initial position, a member normally closing the bottom of the chute, operative connections between both mechanisms above mentioned and the said member, said member being moved by the first mentioned mechanism 30 at a certain period in its movement to open the bottom of the chute, and said member being moved by the aforesaid independent mechanism at a certain period in its movement to close the bottom of the chute.

35 14. In a device of the character described, the combination of a chute having a platen therein, a reciprocating printing device, an inking roller interposed between the printing device and the platen, said inking roller being 40 adapted to be moved out of the path of movement of the printing device upon the forward movement thereof, mechanism for moving the printing device in a forward direction, and independent mechanism for 45 moving the printing device to its initial position.

15. In a device of the character described, the combination of a chute having a platen therein, a horizontally reciprocating printing 50 device, and means for operating the printing device, an inking roller normally positioned between the printing device and the platen, said roller being moved out of the path of the printing device as the same moves forward.

55 16. In a device of the character described, the combination of a chute having an inclined front platen therein, a horizontally reciprocating printing device, the printing surface of which is in the same plane as the inclined platen, means for moving the said printing device, an inking roller normally positioned between the inking device and the platen, said roller being adapted to be engaged by the inclined face of the printing 60 device to push the same out of the path of

movement of the printing device as the said printing device moves forward.

17. In a device of the character described, the combination of a chute comprising a front inclined platen and a rear plate having an opening therethrough, a horizontally reciprocating printing device, the printing face of which extends in a direction parallel with the surface of the inclined platen, means for operating the printing device, an inking roller normally positioned between the printing device and the platen, said roller being moved out of the path of the printing device by engagement with the same as the printing device moves forward. 80

18. In a device of the character described, a chute having a platen therein, a horizontally reciprocating printing device, means for moving said printing device toward the platen, independent means for returning the printing device to its initial position, and an inking roller in the path of the printing device, said inking roller being pushed out of the path as the printing device moves forward. 85

19. In a device of the character described, a chute having a platen therein, a printing device, means for moving said printing device toward the platen, independent means for returning the printing device to its initial 95 position, a member normally closing the bottom of said chute, connections between said member and the means for moving the printing device forward, whereby the said member is moved to open the bottom of the chute, 100 and connections between the said member and the independent means for retracting the printing device, whereby the said member is moved to close the bottom of the chute. 90

20. In a device of the character described, a chute having a platen therein, a printing device, means for moving said printing device toward the platen, independent means for returning the printing device to its initial position, a member normally closing the bottom of said chute, connections between said member and the means for moving the printing device forward, whereby the said member is moved to open the bottom of the chute, 105 connections between the said member and the independent means for retracting the printing device, whereby the said member is moved to close the bottom of the chute, and an inking roller normally in the path of the printing device, said inking roller being 110 adapted to be engaged by the printing surface of the printing device, whereby the inking roller is pushed out of the path of the printing device as it moves forward. 115

In testimony whereof, I hereunto affix my 120 signature in the presence of two witnesses.

GUSTAVE C. KUTZ.
